UNITED STATES PATENT OFFICE.

GEORGE H. DANIELS, OF BAYONNE, NEW JERSEY.

SECTIONAL DIE.

1,402,284.

Specification of Letters Patent. Patented Jan. 3, 1922.

Application filed May 29, 1918. Serial No. 237,192.

To all whom it may concern:

Be it known that I, GEORGE H. DANIELS, a citizen of the United States, residing at Bayonne, in the county of Hudson and State of New Jersey, have invented a new and useful Improvement in Sectional Dies, of which the following is a specification.

This invention relates to dies and my improvements are of special utility when embodied in a sectional die to be used in forming articles of steel or other materials such as plate clips, bars, braces and the like, although I contemplate the use of my invention in any field for which it is adapted by

15 the nature of my improvements.

An important object of my invention is to provide a die built up of interchangeable sections so that provision may be made for performing blanking, forming, punching or 20 shearing operations singly, or a combination of said operations successively without the necessity for setting up the die between said operations.

Another important object of my invention 25 is to provide for the ready removal of a worn punch or die member, without necessitating the renewal of the entire die.

Still another object of importance is to provide for standardizing the parts required 30 in any given shop, so that there may be kept in stock an adequate, interchangeable set or sets of such parts suited to the exigencies of the work in that shop, and requiring a minimum number of die blocks.

35 In providing for the above objects accordingly I have devised a novel arrangement of die blocks which I term a die chase, comprising a male and female member each constructed and arranged to receive interchangeably the constituent parts making up the punch and die required to perform any given operation or series of operations, and I provide also standardized auxiliary parts 40 for use in filling in the spaces of the chase 45 members not occupied by the punch and die members proper; and I also provide standardized members to serve as strippers and guides.

The various features of my invention will 50 be illustrated and described fully in the accompanying drawings and specification and pointed out in the claims.

In the drawings, Figure 1 is a view in end elevation of a sectional die in the construction 55 of which my improvements have been

embodied; Fig. 2 is a view in vertical section upon the line x^2-x^2 of Fig. 3; Fig. 3 is a plan view of the female member of the die shown in Figs. 1 and 2; Fig. 4 is a perspective view upon an enlarged scale of one of the guide and stripper members taken separately; Fig. 5 is a similar view in perspective of one of the spacing members, showing the quoin portion of the structure for retaining purposes; Fig. 6 is a similar view of a modified form of spacing member; Fig. 7 is a plan view similar to Fig. 3 illustrating another application of my novel principle using a central master block.

In the embodiment of my invention selected for illustration and description to permit ready and complete understanding of my improvements, the part designated by the reference character 1 is the male member of a die, and the reference character 2 designates the female member, these parts being of any suitable structure to carry my improvements into effect, and in the instance illustrated the parts thus designated comprise respectively each a chase or frame of metal, of generally rectangular form, having a central opening to receive the operating and spacing members constituting the sectional die proper, in accordance with my invention.

I have selected for illustration a sectional die provided with punch and die members suitable to carry out the operation of punching, shearing and marking on such articles as plate clips, the bar constituting the work blank from which said clips are formed being shown in broken lines and indicated by the reference character 3 in Fig. 2, while the operating parts of the male member are designated respectively by the reference characters 4, 5, 6, 7 and 8, the last mentioned being a shearing blade, while the others are punches suitably positioned each to perform its required operation, these punches passing through a lubricating trough 33.

In accordance with my invention I provide holding members for each of these instrumentalities, the holding members bearing respectively the reference numerals 14, 15, 16, 17 and 18. The holding member may 105 be formed integrally with the operating member as in the case of the member designated 18, where that can be done conveniently, or each punching member may be secured by suitable means to a holding member 110

such as those designated 14 to 17 respectively, the advantage of the separate holder being that where a series of punches having standard shanks can be provided, they may be secured interchangeably to standardized holding members, and thus the number of holding members may be considerably less than the number of the punching members proper, and a greater variety of holding members of 10 different sizes may thus be adapted to a similar great variety of punching members.

Any suitable means may be provided to retain the holding members in the punching chase, and as one convenient form of 15 construction for this purpose I have shown a plurality of set screws 9 passing through the framework of the chase into engagement with bars 10 arranged to distribute the pressure of the set screws over the adjacent members 20 of the die, whether the latter are holders for the punching parts proper, or are merely spacing members, the latter being designated by the reference characters 11 and 12, the members 12 being arranged to 25 receive guides 13 to keep the parts of the die in alinement, these being of any suitable contour and being shown as cylindrical posts in the instance illustrated, their function being that of such well-known guides 30 in the usual die, although it will be observed that my sectional die structure permits of changing the position of these guide members so that they may be located where they 35 will impart the greatest rigidity to the operating punch and die parts while avoiding interference with the operation, and this will be readily understood when it is considered that it might be desirable to perform a punching operation at the corners 40 occupied by these guide members in the illustration, in which event my sectional structure would permit the ready relocation of the guide members at a different portion of the die.

45 The guides 13 are carried by members 113 within the female chase member 2, having spacing members 11, 21, 22 and 31 interposed between them and the female die members 50 and 51, the latter comprising 50 female die members proper, while holding members therefor bear the reference characters 150 and 151.

Set screws 19 and bars 20 may be provided similar in purpose and function to the 55 set screws 9 and bars 10 already described above with reference to the male die member.

The spacing members 11 and 12 are of 60 approximately the same size in the instance illustrated, but larger members 21 and smaller members 22 may be employed as desired, and this subdivision may be carried to any extent required, the character 31 designating a series of very small members immediately surrounding the holding mem-

bers 150 and 151. The filling members are preferably substantially square in cross-section as shown.

In accordance with a notable feature of my invention, this standardization of sectional parts permits the provision of such auxiliary members as the guide and stripping members designated by the reference characters 34, comprising preferably a shank or holding portion 35 of approximately the same size as the adjacent spacing members 31, while the guide portion proper 34 for the work blank may be of any suitable size and contour to direct the work piece 3 as it passes through the die, an overhanging portion 36 serving to strip the work when the punch is raised.

I have shown at 37 a series of punching members, provided with face numbers, to perform the operation of impressing any 85 desired number or other identification mark upon the work piece 3, these members being shown adjacent to the region of operation of the shear members 18, and serving to co-operate with the latter in cutting off the 90 work after it has been stamped. The spacing block 41 of somewhat shorter length is shown, to clear the cutting portion of the shear member 8, and similarly the spacing members 71 may be short in order to permit 95 the completed work to fall freely at the region of discharge.

The member designated by the reference character 61 is a stop carried by two arms 62 secured to the discharge end of the female die chase, the member 61 being a bar placed in the path of the bar or other work blank under treatment, so that when the latter is fed forward it will strike the bar 61, but after the work is completed and the 105 work piece falls down it will pass under the bar 61 and between the brackets 62 and be discharged freely from the die.

I prefer to provide substantially all of the constituent members of the dies with 110 means to aid in their retention at a uniform height within the chase members 1 and 2, as shown, and any suitable form of retaining means may be employed, one such convenient form of construction being provided at 115 30 which designates quoin-like projections upon the respective members, in position to enter retentively grooves 40 upon contiguous members, this quoin and groove arrangement being carried through the entire series 120 of members and operating in a manner clearly illustrated in the drawings, especially in Figure 5 which shows one of the spacing members 21 taken separately, with the quoins 30 and grooves 40 plainly indicated. As a modification of this arrangement, the members may have only grooves 125 as indicated at 130 in Figure 6, which shows a modified form of spacing member bearing the reference character 121, and when thus 130

constructed I have proposed to utilize a separate locking member 140 of suitable diameter and length to enter opposed grooves in contiguous members serving the same 5 purpose as the quoin projections 30 already described.

Figure 7 illustrates one application of my 10 sectional improvements, in which a relatively large central master block or spacing member 211 is shown having openings 202 to reduce the weight, and peripheral grooves 240 to be entered by the retaining quoins 230 upon female die members 200 and corner spacing blocks 212, the spacing member 211 15 having on two of its sides a quoin ridge 330 to enter grooves 340 upon the female die blocks 210 contiguous therewith.

Having illustrated and described my invention thus fully and suitable means by 20 which the same may be carried into effect, I wish it understood that I do not limit myself to the specific materials and structural forms selected for illustration and description, nor in general do I limit myself 25 otherwise than as set forth in the claims read in connection with this specification.

What I claim as new and desire to secure by Letters Patent of the United States is:—

1. In combination, two complementary 30 sectional dies each comprising a die holder, members for performing a desired operation in conjunction with the corresponding member of the other sectional die, pieces surrounding said members for filling the space 35 between said members and said die holders whereby said members may be disposed laterally in any desired position with reference to said die holder, and means for securing said filling pieces and said members within 40 the die holder.

2. A sectional die comprising a plurality of chases, male punching members having holding members and means to secure the same in one of said chases with filling pieces therefor, female punching members, filling 45 pieces and means to hold the same in said other chase, and retaining means comprising quoins and grooves upon said members respectively.

3. In combination, cooperating complementary sectional dies each comprising a die holder, a plurality of members for performing a desired operation in conjunction with those of the other die, pieces surrounding each member for filling the space between 55 said member and the die holder for securing said member in any desired position, certain of said complementary filling pieces being provided with complementary guide posts and guide openings whereby the guides may 60 be positioned as desired within said die holders.

4. In combination, a sectional die comprising a female die holder, a plurality of separate die members, pieces surrounding said 65 members for filling the space between said members and the die holder for securing said member in any desired position, certain of said filling pieces being provided with laterally extending heads disposed adjacent the 70 die members to act as stripping members, and means for securing the die members and the filling pieces within the die holder.

In testimony whereof I have hereunto signed my name in the presence of two sub- 75 scribing witnesses.

GEORGE H. DANIELS.
